UNITED STATES PATENT OFFICE.

HOYT CATLIN, OF FAIRFIELD, CONNECTICUT, ASSIGNOR TO THE BRYANT ELECTRIC COMPANY, OF BRIDGEPORT, CONNECTICUT, A CORPORATION OF CONNECTICUT.

ROTARY SNAP SWITCH.

Application filed June 16, 1921, Serial No. 477,974.

To all whom it may concern:

Be it known that I, HOYT CATLIN, a citizen of the United States of America, residing at Fairfield, in the county of Fairfield 5 and State of Connecticut, have invented certain new and useful Improvements in Rotary Snap Switches, of which the following is a specification.

My invention relates to rotary snap switches, and particularly to improved operating means and switch indicator therefor.

In the accompanying drawings—

Fig. 1 is a perspective of a switch in which my invention is embodied in one 15 form;

Fig. 2 is a vertical section therethrough; and

Fig. 3 is a detached perspective of certain 20 elements of the switch mechanism.

In its main features the present switch is of well known type, comprising an insulating base 5 carrying the binding screw terminals 6 and switch mechanism 7, which may be of any suitable conventional type.

The mechanism comprises a spindle 8 which, at its outer or free end, is squared at 9 and provided with a threaded extension 10. The squared area 9 is engaged by the squared aperture 11 in the yoke 12, which is held 25 against outward pressure of the switch spring 13 by the screw ferrule 14 threaded on the stem 10 and bearing against the outer face of the yoke. Offset from the latter are lugs 15 and 16, preferably of different arcuate extent, which pass through corresponding 30 holes 17 and 18 in the switch cover 19, which serves in the present construction as the means for rotating the switch spindle 8, and thus operating the switch mechanism.

The threaded end 10 of the switch spindle projects beyond the outer face of the cover 19 and receives the holding nut 20, preferably provided with a cross slot 21 to accommodate a screw driver for turning the nut 20 down on the stem. The cover is thus clamped between the yoke 12 and the nut 20, and not only held in position on the switch base but in operative engagement with the lugs 15 and 16 on the yoke 12 encompassing the switch spindle. A circular contour is imparted to the nut 20 to minimize danger of tampering, or accidental removal of the nut from engaging position.

In order to facilitate the operation of the

switch by manipulation of the cover 19, the side wall of the latter is provided with ribs 22 extending outward from a peripheral shoulder 23 and affording a finger grip. The base portion 24 of the cover is cylindrical, and the shoulder 23 is located with particular reference to the insulating base 5 of the switch, so that the ribs 22, or the inwardly offset portion 25 between the ribs 22, do not engage or interfere with the base or the conductors mounted thereon. An insulating lining 26 within the cover effectively insulates the latter from possible contact with the switch structure.

An indication of switch position is readily afforded by locating the ribs 22 at 90° intervals around the switch cover, and printing or impressing in the ribs suitable legends 27 indicative of the position and connection afforded by the switch blades. Thus, the present switch has four distinct positions, 70 in one of which the circuit is broken, while in the other three connections are established to afford low, medium and high heat for a resistance unit suitably connected to the switch. The proper position of the cover with respect to the switch mechanism is assured by the different size of the lugs 15 and 16 on the yoke 12, and the correspondingly different sized holes 17 and 18 in the switch cover. Also associated with the 75 switch is an indicating arrow 28, which may be placed upon any suitable fixed member, such as the frame 29 of a range or heater appliance, or may be formed upon an independent ring 30 mounted on the frame, or 80 on the fixed base of the switch, where the latter is visible. In any event, a suitable locating lug 31 is provided to definitely 85 locate the arrow 28 with respect to the ribs 22.

The particular contour of the switch cover, and the particular formation of the ribs and nut 20 may be varied in many ways without departing from what I claim as my invention.

I claim—

1. A rotary snap switch comprising an insulating base, a switch mechanism mounted thereon and comprising a rotary switch spindle, and a yoke with offset lug on said spindle, in combination with a switch cover 105 pierced to receive said switch spindle and yoke lug, means for securing the cover in

lug-engaging position, and means on the cover for indicating the position of the switch mechanism.

2. A rotary snap switch comprising a rotary switch spindle threaded at one end and having a non-circular area adjacent said threaded end, a yoke upon said non-circular area in the spindle and having offset lugs at its opposite ends, a switch cover pierced to receive said lugs to establish driving relation between the cover and the

spindle, means exterior to the cover and engaging the threaded end of the spindle for holding the cover in engagement with said yoke lugs, together with means associated with said cover for indicating the circuit connections established by the switch on rotation of said cover. 15

In testimony whereof I have signed my name to this specification.

HOYT CATLIN.
